FIG. 8.

UNITED STATES PATENT OFFICE

2,584,207

GEM SETTING AND ARTICLES OF JEWELRY
MADE THEREFROM

Charles Holl, New York, N. Y.

Application July 25, 1950, Serial No. 175,764

3 Claims. (Cl. 63—27)

1

This invention relates to prong settings for diamonds and other precious stones.

Broadly, it is an object of the invention to provide a prong setting or unit for a precious stone and a link to hold such settings together which will permit a necklace, or other article of jewelry, made of such prong settings, a large degree of flexibility laterally.

More particularly, it is an object of the invention to make finer and stronger necklaces and which will allow more light to pass through and be refracted by the stone thus giving greater brilliancy to the stone set within the setting.

Another important object of the invention is to attach the prong post to the outside of the setting unit so as to provide a strong prong to hold the diamond within the setting.

Still another object is to provide opposed prongs fashioned from prong posts attached outside of the setting along an axis 90° to the longitudinal axis of the necklace or bracelet made from such prong settings to give a highly ornamental effect to such necklace or other article of jewelry.

Another object is to provide a setting unit in which the upper edge tapers inwardly leaving a fine outer edge so that when the diamond is set within the setting the outermost circumference or girdle of each diamond practically touches the adjacent diamond to form a continuous chain of diamonds providing an article of jewelry of greater beauty. Since the outside diameter or girdle of the diamond is practically the same as the outside diameter of the setting, larger stones may be used in comparison to the outside diameter and size of the setting than heretofore; that is, larger stones can be used with smaller settings.

Another object is to provide a U-shaped link to hold the settings together, the ends of which are soldered to a single setting giving flexibility and strength to the chain of settings.

Still another object is to provide opposed forked prongs to hold a stone in the setting more firmly.

Another object is to provide double opposed prongs to firmly hold certain sized stones within the setting.

For a fuller understanding of the nature and objects of the invention, reference is had to the following detailed description in connection with the accompanying drawings, in which:

Fig. 1 is a plan view of several settings linked together forming part of a chain or necklace.

Fig. 2 is a plan view of the settings shown in 65

2

Fig. 1 bent arcuately along the longitudinal axis of the chain.

Fig. 3 is a side view of the settings shown in Fig. 1.

Fig. 4 is a sectional view of the settings linked together taken along 5—5 of Fig. 1.

Fig. 5 is a sectional view taken through line 6—6 of Fig. 1.

Fig. 6 is a sectional view taken through line 10 7—7 of Fig. 3.

Fig. 7 is a bottom view of two links of the settings.

Fig. 8 is an end view of a single setting without a stone set within the setting and before the 15 prongs are bent inwardly.

Fig. 9 is a plan view of a stone set within a modified setting, the opposed prongs being forked.

Fig. 10 is a plan view of a stone set within another modified setting, showing four prongs, two 20 opposed on each side.

Referring to the drawing, numeral 10 represents five settings of a necklace or a like piece of jewelry each setting comprising a hollow cylindrical form 11 having two opposed cylindrical posts 12 attached to the outside wall of the cylindrical setting 11 by brazing, soldering, or other well known means, upon an axis at right angles to the longitudinal axis of the necklace. The posts 12 extend above the upper wall of the cylindrical form or setting 11 forming opposed prongs

30 13 which are adapted to be bent inwardly to hold a diamond or other precious stone 14, as best shown in Fig. 5. A means of firmly attaching the posts 12 to the setting or form 11 is to provide two 35 opposed vertical semi-circular channels of the same radius as the posts 12 and then soldering the posts 12 within the channels so formed, as best shown in Fig. 7. The radius of the posts 12 should be less than the thickness of the wall of the cylindrical form or setting 11 so that the post 12 does not weaken the form or setting 11. A

40 pair of opposed slits 15—15 are provided in the setting or form 11 which run parallel to the longitudinal axis of the necklace, the slits 15 being preferably below the horizontal center of the form or setting 11 providing a bridge-like portion 16 between each end of the slits 15.

The upper wall 17 of the setting 11 is tapered inwardly and downwardly from the upper outer 50 circumference of the setting 11 at approximately the angle of the base of the stone 14 so that a knife-like edge 18 is formed around the upper outer circumference of the setting 11. The inner wall 19 of the prongs 13 may be slightly 55 tapered upwardly, as shown in Fig. 8 so that the

largest diameter or girdle of the stone 14 will fit snugly upon the upper knife-like edge 18 and the outermost circumference of the stone 14 will coincide with the circumference of the setting 11 and the knife-like edge 18.

A U-shaped link 20 having a semi-circular end 21 and a pair of opposed legs 22 is attached to the setting 11 by inserting the legs 22 into the opposed slits 15 on either side of the bridge-like portion 16 with the end 21 projecting outwardly from the setting 11 at right angles to the vertical axis of the setting 11, and on each side of the longitudinal axis 23 of the necklace. Each setting 11 is disposed so that the projecting link 20 has its end 21 encircle the free bridge-like portion 24 of the adjacent setting 11. The legs 22 are preferably soldered in the position shown best in Fig. 7 to the setting 11 and their ends 25 ground down to coincide with the inner circumference 26 of the setting 11. Link 20 is long enough so that the outer circumferences of the settings 11 touch one another and allow the settings 11 to roll one upon the other permitting free limited movement between adjacent connected settings laterally, as shown in Fig. 2 giving the necklace a large degree of flexibility and making a particularly strong linkage for the setting 11. Prongs generally fashioned from the same material as the housing or setting for the stone are not as strong as the prongs heretofore described.

It should be particularly noted that the posts 12 are attached to the outside wall of the setting. The posts 12 can thus be of sufficient diameter to impart great strength to the prongs 13 while providing a pair of opposed semi-circular projections paralleling the longitudinal axis of the necklace 10 giving an interesting and decorative effect to the article of jewelry.

It should also be noted that only a small portion of the U-shaped end 21 of the link extends into the hollow of the setting 11 so that a maximum amount of light passes through the stone 14 and the setting thus giving greater brilliancy to the stones than was heretofore obtainable.

By providing a knife-like upper edge 18 for the setting with the upper wall 17 tapered inwardly the largest diameter or girdle of the stone 14 can rest upon the edge 18. Since the settings 11 touch one another, the stones 14 can touch one another giving a continuous line of stones and permitting very small settings to be used with stones of larger diameters than stones used in comparable settings. Furthermore, the stones 14 may be set lower because of the tapered upper wall 17 at the same time providing a better seat for the stone.

After the stone 14 is lowered into the setting 11, the prongs 13 are bent inwardly upon the upper taper 27 of the stone. The outer edge 28 of the prong 13 is then rounded by filing or polishing, as shown in the figures.

In Fig. 9, a modification of the prongs 13 is shown. The upper portion of the prong 12' is split and bent to the right and left of the lateral axis thus spreading the points of contact with the stone and holding it more firmly within the setting.

In Fig. 10 a further modification is shown, wherein four prongs 12'' are used, two on each opposed side of the setting. For use with larger settings and stones it may be desirable to use four prongs to be sure that the stone is more firmly held within the setting. Of course, each

of the four prongs 12'' may be split like 12', shown in Fig. 9, if desired.

The prongs 12' and 12'' are extensions from the posts below like those shown in the previous figures and such posts and prongs are also attached to the outside circumference of the setting.

It is obvious that modifications and changes may be made in the details of construction without departing from the general spirit of the invention.

I claim:

1. A setting for a necklace or the like in combination with a stone, said setting comprising a hollow cylindrical form having its upper wall tapering inwardly and downwardly leaving an outer sharp edge, the outer circumference of said stone being equal to the outer circumference of said setting, said setting having opposed slits perpendicular to the longitudinal axis of said setting, a bridge between and at each end of said slits, means for retaining said stone on said setting, said means comprising solely a pair of opposed vertical prong posts attached to the outside of said setting parallel to the axis of said setting, said prong posts extending above the upper edge of said setting and bent inwardly over a portion of said stone, said prong posts in a plane at right angles to the plane of said bridges, a U-shaped fastening link, said link having a semi-circular end and a pair of opposed legs of equal length projecting beyond the circumference and at right angles to the axis of said setting, said legs within said opposed slits and on either side of one of said bridges and attached to said setting.

2. In a necklace or the like, the combination of a plurality of like settings in a single row and a stone in each setting, each said setting comprising a hollow cylindrical form having its upper wall tapering inwardly and downwardly leaving an outer sharp edge, the outer circumference of each of said stones being equal to the outer circumference of each of said settings, each of said settings having opposed slits perpendicular to the longitudinal axis of said settings, a bridge between and at each end of said slits, said slits below the horizontal center of said setting, opposed vertical prong posts attached to the outside of each of said settings parallel to said axis of said settings and in diametrical plane at right angles to the longitudinal axis of the necklace, said prong posts extending above the upper edge of said settings and bent inwardly to hold said stone within each of said settings, each setting having a U-shaped fastening link, each of said links having a semi-circular end and a pair of opposed legs of equal length, said legs within said opposed slits and on either side of one of said bridges, said legs attached to said setting, a small portion of the semi-circular end of said links appearing within said hollow cylindrical form and projecting at right angles to the vertical axis of said settings and on each side of the longitudinal axis of said necklace, the said settings being so disposed that the projecting link of one of said settings encircles a free bridge of the adjacent setting whereby the settings are movably connected permitting said necklace flexibility laterally.

3. In a necklace or the like, the combination of a plurality of like settings in a single row and a stone in each setting, each said setting comprising a hollow cylindrical form having its upper wall tapering inwardly and downwardly leaving an outer sharp edge, the outer circumference of each of said stones being equal to the outer circumference

ence of each of said settings, each of said settings having opposed slits perpendicular to the longitudinal axis of said settings, a bridge between and at each end of said slits, said slits below the horizontal center of said setting, opposed vertical prong posts attached to the outside of each of said settings parallel to said axis of said settings and in diametrical plane at right angles to the longitudinal axis of the necklace, said prong posts extending above the upper edge of said settings, the upper part of said prong posts split forming prongs bent inwardly to the right and left of the lateral axis of said settings to hold said stone within each of said settings, each said setting having a U-shaped fastening link, each of said links having a semi-circular end and a pair of opposed legs of equal length, said legs within said opposed slits and on either side of one of said bridges, said legs attached to said setting, a small portion of the semi-circular end of said links ap- 20

pearing within said hollow cylindrical form and projecting at right angles to the vertical axis of said settings and on each side of the longitudinal axis of said necklace, the said settings being so disposed that the projecting link of one of said settings encircles a free bridge of the adjacent setting, whereby the said settings are movably connected so that the stones lie face up on the neck of the wearer permitting said necklace lateral flexibility.
